GEORGE F. WENTZ, OF CLEVELAND, OHIO, ASSIGNOR, BY DIRECT AND MESNE ASSIGNMENTS, TO THE WENTZ YODER MANUFACTURING COMPANY, OF CLEVELAND, OHIO. A CORPORATION OF OHIO.

THERMOSTATIC VALVE.

1,088,193.

Specification of Letters Patent. Patented Feb. 24, 1914.

Application filed June 29, 1912. Serial No. 706,727.

To all whom it may concern:

Be it known that I, GEORGE F. WENTZ, a citizen of the United States, residing at Cleveland, in the county of Cuyahoga and State of Ohio, have invented a new and useful Thermostatic Valve, of which the following is a specification.

This invention has reference to improvements in thermostatic valves, and its object is to provide a valve for the control of fuel, particularly gaseous fuel, whereby the heat generated may be automatically controlled within very narrow limits.

The valve is designed more particularly for use in connection with steam generators where gas is used as fuel, and the heat of the water or steam is employed as the controlling agent for operating the valve structure, while in the valve of the present invention the use of springs and other structures liable to get out of order or to become clogged or otherwise rendered useless is avoided.

The thermostatic portion of the present invention comprises two elements of different thermo expansibility and preferably one of the elements is responsive to heat to a minimum extent, while the other element approaches the maximum, wherefore the responsiveness of the device to changes in heat is due almost entirely to the response of one of the thermostatic elements. The movement thus brought about is transmitted through a system of levers operating solely by gravity in those movements which tend to cut off the supply of gas to the burner, the arrangement being such that the valve will respond to a very few degrees change in heat or a very few pounds difference in steam pressure as exhibited in changes in heat from full open to full closed position. Furthermore, the port controlling member of the valve is so arranged that the liability of lodgment of particles of dirt or other matter upon a valve seat is practically *nil*.

The invention will be best understood from a consideration of the following detailed description taken in connection with the accompanying drawings forming a part of this specification, with the further understanding that while in the drawings there are shown different practical forms which the invention may assume, it is sus-

ceptible of other practical embodiments, wherefore the invention is not confined to any strict conformity with the showing of the drawings, but may be changed and modified within such limits which do not mark a material departure from the salient features of the invention.

In the drawings:—Figure 1 is a side elevation of a structure embodying the present invention. Fig. 2 is a longitudinal central vertical section of the structure shown in Fig. 1. Fig. 3 is a section on the line 3—3 of Fig. 2. Fig. 4 is a longitudinal section of a compound lever structure of the gravity type employed in the structure of Fig. 1. Fig. 5 is a view of one member of the thermostatic element. Fig. 6 is a view similar to Fig. 2 but illustrating another practical embodiment of the invention.

Referring to the drawings, there is shown a body member 1 which may be in the form of a casting of suitable material, such as brass or iron, and this body member has an internal chamber 2 closed at one end by a head 3 and at the other end normally closed by a screw plug 4, this plug providing means for ready access to the chamber 2 when desired. On opposite sides of the chamber 2 are necks 5 and 6, respectively, designed to receive pipes 7, 8, through which the fuel is directed, such fuel being customarily gas, entering one of the pipes and flowing out through the other, the outflow being toward the burner which is employed to furnish heat to what in the particular instance under consideration may be assumed to be water to be converted into steam, it being further assumed that the device is attached to a steam generator of any appropriate type. For the purpose of securing the device to a steam generator the head 3 is provided with an axial neck 9 exteriorly threaded, and entering this neck in axial alignment therewith is a tube 10 opening at one end into the chamber 2 and closed at the other end, as indicated at 11. What ever be the material of which the body 1 is composed, the tube 10 is made of some material having a considerable degree of expansibility under the action of heat, and it may be stated that copper answers the purpose of the present invention, although other materials may be used. Lodged within the tube

10 is a rod 12 preferably of a material responding so slightly to the action of heat so far as expansibility is concerned that within the range of temperature to which 5 the device is subjected the rod 12 may be considered as not expanding at all. A carbon or porcelain rod will answer the purposes of the present invention. To protect the ends of the rod 12 from liability of injury one end is provided with a metallic cap 13 and the other end with a metallic cap 14, the latter being provided with an exterior pocket 15 for a purpose which will presently appear. The tube 10 may be secured to the 10 neck 9 in any suitable manner, as, for instance, by soldering, since the heat to which the device is subjected is not high enough to materially affect a solder joint.

Where the neck 5 joins the body 1 there 20 is provided a web 16 formed at its middle portion with a passage 17 about which there is formed a circular flange 18 entering the neck 5 for a distance and constituting a seat for a valve 19, the latter in the form shown 25 in Figs. 2 and 3 being a ball valve. This valve 19 may be so related to the pipe 7 that the latter will act as a cage preventing too great a displacement thereof, while the portion of the neck entered by the pipe 7 is 30 of sufficiently large diameter to permit the introduction of the valve when the pipe 7 is not present.

Within the chamber 2 is a lever 20 of comparatively massive proportions, and 35 mounted on a pin 21 as a pivot or fulcrum, this pin being carried by the body 1. The pin 21 is located close to one end of the lever, so that there is a great preponderance of weight with respect to the longer arm 40 of the lever, this weight being far in excess of any resistance to the movement of the lever under the action of gravity which might be presented to such movement by corrosion of the pin 21 or the body of the 45 lever where surrounding the pin, or at any other point where a resistance to movement of the lever is not purposely present. Extending longitudinally through the lever 20 to one side of the pivot pin 21 is a screw 50 22 having an end 23 extending through and beyond the shorter arm of the lever and entering the pocket 15 so that the rod 12 acts to maintain the lever 20 in an approximately horizontal position when the device 55 is in use, the shape of the lever 20 and the disposition of the pivot pin 21 and screw 22 being such as to constitute the lever 20 a bell crank lever with a longer arm of greatly preponderant weight. Mounted on 60 the longer arm of the lever 20 is another lever 24 which may be in the form of a plate having an offsetting ear 25 on one side entering a suitable recess 26 in the lever 20 and connected to the latter by a pivot pin 65 27. The lever 24 is of the third order with

one arm longer than the other and the longer arm extending above the lever 20, when in operative position, toward the pivot pin 21. Near the free end of the longer arm of the lever 24 there is secured a pin 28 in position 70 to enter the passage 17 and engage the ball valve 19 under circumstances to be described. Extending through the body 1 is a set screw 29 so located as to be in the path of that end of the lever 24 remote from the pin 28, and this set screw, which serves as an adjustable or variable fulcrum, is provided with a lock nut 30 for holding it in adjusted positions.

Extending through the neck 5 which may 80 be provided with a boss 31 for the purpose, is a screw 32 having a taper point 33 constituting a valve adapted to a valve seat 34 through which communication may be had between the chamber 2 and the interior of 85 the neck 5. Formed in the neck 5 is a passage 35 suitably tapped for the reception of a pipe 36 which may be continued to a pilot flame if such be desired. The valve screw 32 is designed to provide for the feeding of a 90 pilot flame when the valve 19 is in the closed position.

Let it be assumed that the device so far described is installed on a steam boiler with the pipe 10 either entering water within the 95 boiler or the steam chamber within the boiler. While the parts are cold and the pipe or tube 10 is in the contracted position the set screw 29, which may be initially set to cause the opening of the valve 19 is manipulated until the gas flame at the burner is cut down by the closing of the valve 19 until fed only by the pilot flame determined by the degree of opening of the valve end 33 of the valve screw 32 with relation to the 100 valve seat 34. Now the screw 29 is turned sufficiently to cause the opening of the valve 19 to provide the full feed of gas to the burner and the screw 29 is then locked in 105 such position by the lock nut 30 to prevent accidental displacement. As the heat of the water or steam increases the tube 10 is elongated and the preponderance of weight of the lever 20 is amply sufficient to cause the 110 rod 12 to follow up the tube 10 as it elongates. The long end of the lever 24 not only by its own weight, but because of the weight of the valve 19, will tend to approach the lever 20 as the long end of the latter drops and the other end of the lever 24 tends to 115 move away from the stop screw 29, the rocking of the lever 24 under the circumstances just mentioned, however, maintaining engagement of the short end of the lever 24 with the screw or fulcrum 29. The increasing length of the pipe or tube 10 will cause a corresponding movement of the lever 20 under the action of gravity until ultimately the valve 19 seats on the upper end of the flange 18, thus cutting off the supply of gas 120 125 130

to the burner except that furnished through the pilot valve 32. In practice, however, the entire cutting off of the gas supply except through the pilot valve need not occur, but 5 comparatively minute variations in heat will be taken care of by the device described. Sometimes the rods 12 may become broken, or they may vary in different valves, or again, when a broken rod is replaced by an 10 unbroken one the latter may not be of the same length as the one it replaces. Such variations are readily taken care of by the screw 22 so that the gravity lever 20 may be adjusted to the best position for operation.

15 It will be observed that springs are entirely eliminated and their variations under different circumstances are avoided. The gravity lever 20 with its supplemental lever 24 producing thereby a compound lever is 20 sensibly constant in action and may be readily made of such preponderant nature that it will overcome all accidental forces or conditions tending to prevent its proper operation.

25 The valve seat formed by the flange 18 is elevated above the web 16 and the valve 19 laterally overhangs this valve seat, so that the liability of interfering particles lodging on the valve seat is reduced to a negligible 30 minimum. Furthermore, the interior of the valve body or casing is readily accessible and adjustments may be made with the greatest facility.

The structure of Fig. 6 is in part the same 35 as the structure already described and the same reference numerals are employed wherever applicable. The structure of Fig. 6 differs from that of Fig. 1 and associated figures in the provision of a multiple lever 40 instead of a compound lever of two coacting elements. Instead of a neck 5 the structure of Fig. 6 is provided with a longer neck 5^a and within the neck there is formed an extension 2^a of the chamber 2. In this chamber 2^a there is mounted a lever 37 supported 45 near one end of a pivot pin 38 extending through the neck 5^a above the pivot pin 21 of the lever 20 and also at a point higher than the longer end of the lever 24. Adjacent 50 the pivot pin 38 the lever 37 carries a roller 39 and at the end of the lever 37 remote from the pivot pin 38 the lever carries a pivot pin 40 traversing an ear 41 offset from a lever 42 having a shorter arm 43 in 55 the path of a set screw 44 entering the neck 5^a and accessible from the exterior thereof and provided with a lock nut 45. Within the neck 5^a there is formed a web 16^a having a central passage 17^a surrounded by an up- 60 standing flange 18^a at the upper end of which there is formed a seat for a valve 19^a having its edges in overhanging relation to the valve seat. This valve is traversed by a valve stem 46 fast thereto and connected by 65 a link 47 to the longer end of the lever 42,

said link extending through the passage 17^a. A set screw 48 is located in position to engage the shorter end of the lever 24 and is mounted in an appropriate portion of the neck 5^a and is accessible from the exterior of the neck for manipulation. The set screw 48 operates as does the set screw 29 in the form shown in Fig. 1. While in the structure shown in Fig. 6 no pilot valve is disclosed, it will be understood that the pilot 70 valve is assumed to be present. 75

The operation of the structure shown in Fig. 6 is in effect similar to the operation already described with relation to Fig. 1 and associated figures, adjustments being accomplished by the set screws 44 and 48, the final adjustment being brought about by the set screw 44 which performs a function similar to the set screw 29 of the form shown in Fig. 1. The structure shown in Fig. 6 is responsive to far less variations in movement of the tube 10 than is the case in the structure shown in Fig. 1, the multiple lever system of Fig. 6 in practice increasing the movement of the tube 10 by about fifty 80 times at the valve 19^a which is four or five times the multiplication of movement brought about by the structure shown in Fig. 1. 85

Aside from the greater sensitiveness of 90 the structure of Fig. 6 over a structure of Fig. 1 and associated figures the various advantages inherent in the structure of Fig. 1 are present in the structure of Fig. 6. The form of thermostatic regulator illustrated in 95 Fig. 1 and associated figures in its practical embodiments causes a movement of the valve from full open to full shut on an expansion of the length of the tube 10 of about one-eighthieth of an inch, while the more sensitive structure shown in Fig. 6 responds to a change in pressure represented by a corresponding change in temperature of but a very few pounds, say one or two pounds, or 100 a close approach thereto. 105

110 What is claimed is:—

1. In a thermostatic valve, a thermostat, a valve member movable to open and closed positions, and a motion multiplying lever comprising a plurality of elements one carried wholly by the other, one of the elements being engaged by the thermostat and the other acting on the valve and both movable solely by gravity toward the position causing the closing of the valve. 115

2. In a thermostatic valve, a thermostat, a movable valve member for opening and closing a passage through the valve structure, a lever having one end in position to be engaged by the thermostat, another lever wholly carried by the first named lever and provided with a longer arm directed toward the fulcrum of the first named lever, means between the long end of the second named lever and the valve member for mov- 120 125 130

ing the latter to open and close the passage through the valve structure, and stop means in the path of the second lever.

3. In a thermostatic valve, a thermostat, a movable valve member for opening and closing a passage through the valve structure, a lever having one end in position to be engaged by the thermostat, another lever wholly carried by the first named lever and provided with a longer arm directed toward the fulcrum of the first named lever, means between the long end of the second named lever and the valve member for moving the latter to open and close the passage through the valve structure, and stop means in the path of the second lever constituting a fulcrum therefor, the first named lever being provided with adjusting means for accommodating it to mechanical variations in the thermostat.

4. In a thermostatic valve structure, a chambered body member, a thermostat carried thereby and opening into the chamber, a lever of the first order mounted in said chamber, another lever of the third order carried by the longer arm of the first named lever, a port controlling valve member carried by the valve structure, means controlled by the longer arm of the second named lever for closing or opening the valve member, and an adjustable fulcrum in the path of the second named lever and carried by the body member.

5. In a thermostatic valve structure, a chambered body member, a thermostat carried thereby and opening into the chamber, a lever of the first order mounted in said chamber, another lever of the third order carried by the longer arm of the first named lever, a port controlling valve member carried by the valve structure, means controlled by the longer arm of the second named lever for causing the opening and closing of the valve member, and an adjustable fulcrum in the path of the second named lever and carried by and exposed for access on the exterior of the body member, the first named lever being provided with an adjusting screw for engaging the thermostat to accommodate the lever to mechanical variations in the thermostat.

6. A thermostatic valve comprising a chambered body member having a passage therethrough for fuel and a removable valve member controlling said passage, a thermostat carried by the body member, a removable member for closing the chambered portion of the body member, a lever of the first order within the chamber and accessible on the removal of the closure for the chamber, another lever of the third order carried by the long arm of the first named lever and having a long arm extending toward the fulcrum of the first named lever, means between the long arm of the second

named lever and the movable valve member for controlling the latter, and relatively fixed means in the path of that end of the second named lever remote from the valve controlling end thereof for causing said lever to rock on its pivot support on the first named lever.

7. In a thermostatic valve structure, a thermostat, a movable valve member for controlling the passage of fluid through the valve structure, and a compound lever of which one member wholly carries another member, the carrying member being under the control of the thermostat and the carried member in turn operating to control the movable valve member.

8. In a thermostatic valve, a thermostat, a valve member movable to open and closed positions, a motion multiplying compound lever comprising a plurality of elements, of which one is carried wholly by the other with one of the elements engaged by the thermostat and the other element having connections acting on the valve, and an adjustable fulcrum for a member of the compound lever.

9. In a thermostatic valve structure, a movable valve member for controlling the flow of fluid through the valve structure, a thermostat carried by the valve structure, and a compound lever having one member wholly carrying another member and in turn engaged by the thermostat for actuation thereby and a motion multiplying connection between the compound lever and the movable valve member.

10. In a thermostatic valve structure, a movable valve member for controlling the flow of fluid through the valve structure, a thermostat carried by the valve structure, a compound lever having one member wholly carrying another member and in turn engaged by the thermostat for actuation thereby and a motion multiplying connection between the second lever member and the movable valve member, said motion multiplying connection comprising a compound lever having one member wholly carried by another member.

11. In a thermostatic valve structure, a movable valve member, a thermostat, a lever controlled by the thermostat and having one end enlarged to cause a movement of the lever in one direction wholly by gravity, another lever mounted on the first named lever, a relatively fixed member in the path of one end of the second lever, a third lever in the path of the second lever, a fourth lever carried by the third lever, a relatively fixed member in the path of the fourth lever, and connections between the fourth lever and the movable member of the valve.

12. In a thermostatic valve structure, a movable valve member, a thermostat, a lever controlled by the thermostat and having one

end enlarged to cause a movement of the lever in one direction wholly by gravity, another lever mounted on the first named lever, a relatively fixed member in the path of one end of the second lever, a third lever in the path of the second lever, a fourth lever carried by the third lever, a relatively fixed member in the path of the fourth lever, and connections between the fourth lever and the movable member of the valve, the relatively fixed members in the paths of the second and fourth levers being mounted

for adjustment and the first named lever being provided with an adjustable means for adapting the first named lever to mechanical differences in thermostatic elements.

In testimony, that I claim the foregoing as my own, I have hereto affixed my signature in the presence of two witnesses.

GEORGE F. WENTZ.
